MANUALLY ADJUSTABLE FOOTRAIL

Filed Aug. 28, 1945

UNITED STATES PATENT OFFICE

2,561,091

MANUALLY ADJUSTABLE FOOTRAIL

Alfred B. Bell, Philadelphia, Pa., assignor to Heywood-Wakefield Company, Gardner, Mass., a corporation of Massachusetts

Application August 28, 1945, Serial No. 613,064

4 Claims. (Cl. 155—171)

1

This invention relates to a foot rail adapted to be mounted at the backs of chairs for the use of the occupants of the chairs immediately behind those which carry the foot rails. It is an object of the invention to provide a foot rail which can be adjusted to different elevations by the manipulation of a handle on the chair which carries the foot rail, the handle being placed within easy reach of the user of the foot rail.

Another object of the invention is to provide a foot rail having an adjusting mechanism which permits elevation of the rail from any position of adjustment by a lifting force acting directly on the rail. For example, the user can hook his toe under the rail and elevate it. Furthermore, if the foot rail is mounted on a rotatable chair in such a way that the rail in its lower positions of adjustment will strike a corner of the pedestal when the chair is rotated, the rail will yield upwardly and avoid injury to itself or to the pedestal.

For a more complete understanding of the invention, reference may be had to the following description of an embodiment thereof and to the drawings, of which:

Figure 1 is a side elevation of a vehicle chair carrying a foot rail mechanism embodying the invention.

Figure 2 is a rear elevation of the same.

Figure 3 is a fragmentary section on the line 3—3 of Figure 2.

Figure 4 is a section on the line 4—4 of Figure 3.

Figure 5 is a section on the line 5—5 of Figure 2.

Figure 6 is a section on the line 6—6 of Figure 5.

The drawing illustrates a vehicle chair suitable for use in a railway car or the like and comprising a seat 10, a back 12, side frames 14, arm rests 16 and a pedestal 18, the latter being preferably fastened to the floor. The chair may be provided with any desired type of reversing mechanism (not shown) by which it may be swung around on its pedestal to face in the opposite direction.

A foot rail 20 is carried by the chair at the rear thereof for use of the occupant of the chair next behind. The rail 20 is supported by bracket arms 22 at its ends, these arms being secured to a shaft 24 which is rotatable in bearing members 26 mounted on the frame of the chair. Mounted on the shaft is a gear wheel 28 which meshes with a rack 30. For convenience of manufacture and adjustment, the rack 30 is made in the form of a screw thread or worm, formed on a

2

rod 32. The rod 32 does not rotate in use but moves axially within a tubular guide member 34 which is supported by a pair of ears 36 through which the shaft 24 projects, permitting variation of the angular position of the rod 32 with respect to the shaft 24.

The upper end of the rod 32 is pivotally attached to an arm 38 projecting from a lever 40 at an intermediate point thereof. The lever 10 swings about a pivot 41 at its lower end on one of the side frames 14.

The upper portion of the lever 40 is a plunger 44 which is in telescoping relation to the lower portion, being slidable in an axial bore 42. The plunger 44 is pressed outward by a compression spring 46 seated in the bore 42 and bearing against the inner end of the plunger, but the movement of the plunger is limited by a pin 48 which projects laterally therefrom and rides in a short longitudinally extending slot 50 in the wall of the lever 40. The plunger 44 extends through a slot 52 in an arcuate top plate 54 at the rear end of the arm rest 16 concentric with the pivot 41. The top plate 54 thus forms a housing in the rear of the arm rest 16. The plunger terminates in a knob or handle 56 on the end which projects beyond the top plate 54 and is within easy reach of the occupant of the chair next behind.

The sides of the slot 52 are notched at intervals as at 58, these notches being shaped and arranged, as shown in Figure 6, to form with portions of the slot itself a series of semicircular openings so that the plate 54 is essentially a rack adapted to receive a pawl 60 which is in the shape of a semicircular block or collar fixed on the plunger 44 where it passes through the slot 52. When the plunger is pressed by the spring 46 to its outer position, the pawl 60 engages in one of the semicircular openings and holds the lever 40 in a corresponding position of angular adjustment.

The rectilinear edges 62 of the notches 58 are undercut at 64 (Figure 5), this undercut bevelled surface being engaged by a complementary bevelled surface 66 on the pawl 60. If, therefore, a lifting force is applied to the rail 20, this tends to swing the lever 40 in a clockwise direction about its pivot. The bevelled surfaces 64 and 66 exert a camming action on the plunger 44 tending to press it inward against the spring 46. If sufficient force is exerted, the plunger is forced inward to release the lever 40 to move until the pawl 60 catches in another of the series of semicircular openings indicated in Figure 2.

The knob 56 is adapted to be pressed manually to force the plunger 44 inward. This releases the lever 40 for movement in either direction by manipulation of the knob 56.

The foregoing description of an embodiment of the invention is for illustration and not limitation, and it is to be understood that the scope of the invention is to be measured by the following claims.

I claim:

1. In combination with a chair, a shaft rotatably mounted at the rear of said chair to rotate about a horizontal axis, a foot rail mounted on said shaft, a pinion mounted on said shaft coaxially therewith, a rack slidable within guide means carried by the chair and said rack being meshed with said pinion, a lever rockably mounted on said chair and pivotally connected to said rack to move said rack longitudinally when the lever is rocked, and ratchet and pawl means carried by said chair and lever and arranged to permit free movement of the lever in one direction only.

2. In combination with a chair having an arm rest, a housing at the rear end of said arm rest having an arcuate wall portion with a slot therein, an operating lever projecting through said slot in the housing and having a knob at its outer end, said operating lever having its other end pivotally mounted on said chair whereby the lever may slide in the housing, a rack slidable within guide means carried by the chair and connected at one end to said lever, a pinion rotatably mounted on said chair in mesh with said rack whereby longitudinal movement of said rack by operation of said lever causes said pinion to rotate, and a foot rail rockably mounted on said chair and operatively connected to said pinion for rocking movement therewith to different positions of adjustment.

3. In combination with a chair having an arm rest, a foot rail mounted at the rear of said chair to rock about a horizontal axis, a lever pivotally mounted at the rear end of said arm rest, a

linkage connecting said lever and foot rail so that the lever and foot rail rock in unison, and ratchet and pawl means on said lever and chair cooperating to hold said foot rail against downward movement, said lever having a telescoping structure operable to release said pawl to allow downward rocking movement of the foot rail.

4. In combination with a chair, a horizontal shaft rockably mounted at the rear of said chair, a foot rail secured to said shaft to rock about the axis thereof, a pinion mounted on said shaft, a rack in mesh with said pinion and longitudinally movable to rotate said shaft thereby rocking the foot rail, a lever pivoted at one end to said chair at the rear thereof and at the other end pivotally connected to the said rack, a spring-pressed plunger projecting upward from the lever, a pawl with a bevelled edge carried by said plunger, a handle at the outer end of said plunger, and a ratchet member having notches with bevelled edges engageable by the bevelled edge of said pawl to permit upward movement of said rail by force applied directly to the rail and to release the rail for movement up or down when the handle is pressed to disengage the pawl from the ratchet, and elevated or lowered to drive the said rack.

ALFRED B. BELL.
